UNITED STATES PATENT OFFICE.

WILLIAM E. EDWARDS, OF BROOKLYN, NEW YORK.

DESIGN FOR A BADGE.

No. 39,335.

Specification for Design.

Patented June 9, 1908.

Application filed April 10, 1908. Serial No. 426,398. Term of patent 7 years.

To all whom it may concern:

Be it known that I, WILLIAM E. EDWARDS, a citizen of the United States, and a resident of Brooklyn, county of Kings, and State of New York, have invented a certain new, original, and ornamental Design for Badges, of which the following is a specification, reference being had to the accompanying drawing, forming a part thereof.

The drawing shows a plan view of the badge illustrating my new design.

I claim:

The ornamental design for a badge as shown.

WILLIAM E. EDWARDS.
